CLAIM

The ornamental design for a combination power storage and wireless device, as shown and described.

DESCRIPTION

FIG. 1 is a bottom perspective view of the combination power storage and wireless device, showing the new design; FIG. 2 is a bottom perspective view of the combination power storage and wireless device, shown in a condition of use;

FIG. 3 is a top perspective view of the combination power storage and wireless device;

FIG. 4 is a top perspective view of the combination power storage and wireless device, shown exploded for clarity of disclosure;

FIG. 5 is a front elevational view of the combination power storage and wireless device;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines on the combination power storage and wireless device depict portions of the combination power storage and wireless device not part of the claimed design. In FIG. 2, the broken lines showing a mobile phone and a cord depict environmental subject matter only, and form no part of the claimed design.
